UNITED STATES PATENT OFFICE.

KARL ZALLUD, OF NEW YORK, N. Y., ASSIGNOR TO LOUIS SCHULTZ AND JOHN B. HAGENBUCHLE, OF SAME PLACE.

QUILTING-MACHINE.

SPECIFICATION forming part of Letters Patent No. 376,621, dated January 17, 1888.

Application filed March 20, 1886. Serial No. 195,934. (No model.)

To all whom it may concern:

Be it known that I, KARL ZALLUD, of New York, in the county and State of New York, have invented a certain new and useful Improvement in Quilting-Machines, of which the following is a specification.

My improvement relates to machines for quilting patterns upon fabric.

I will describe a quilting-machine embodying my improvement, and then point out the novel features in the claims.

In the accompanying drawings, Figure 1 is a rear elevation of a quilting-machine embodying my improvement. Fig. 2 is a plan or top view of the same. Fig. 3 is a transverse section taken on the plane of the line *x x*, Fig. 2, and looking in the direction of the arrow *b*, the same being drawn to a larger scale than that of Figs. 1 and 2. Fig. 4 is an elevation of a portion of certain reversing mechanism employed in the machine. Fig. 5 is an end view of the same. Fig. 6 is a horizontal section of a portion of the mechanism for actuating the shuttles, taken on the plane of the dotted line *y y*, Fig. 3. Fig. 7 is a sectional elevation of the same taken on the plane of the dotted line *z z*, Fig. 6. Fig. 8 is a detail view of mechanism I employ for quilting various patterns on the goods. Fig. 9 is a section thereof taken on the plane of the dotted line *c c*, Fig. 8. Fig. 10 is a diagram showing the pattern formed by the use of such device. Fig. 11 is a diagram showing another pattern quilted by the machine. Figs. 12 and 13 illustrate modified means for imparting motion to certain carriages employed on the machine, a portion of each being broken away to save space. Fig. 14 is a side elevation looking from the right of Fig. 1. Fig. 15 is a side elevation looking from the left of Fig. 1. Fig. 16 is a horizontal section taken just above the needle-plates. Fig. 17 is a perspective view, on an enlarged scale, of a portion of one of the shuttle-races and the complementary mechanism. Fig. 18 is a transverse section, on an enlarged scale, of similar parts to those shown in Fig. 17.

Similar letters of reference designate corresponding parts in all the figures.

A A' designate the side portions of the frame of the machine. B is the main driving-shaft, located at the rear of the machine and having

motion imparted to it from a belt upon a pulley, B'.

I will first describe the sewing mechanism and the means for actuating the same. In this machine I employ more than one needle-bar and gang of needles. I have shown five such needle-bars and gangs of needles with coacting parts. I may, however, use two, or any desired number more than one. Each of these 60 needle-bars has a traverse from side to side of the machine. Certain of the needle-bars move in one direction while certain of the other needle-bars are moving in the opposite direction. In other words, certain of the needles 65 are sewing from right to left at the same time that others are sewing from left to right. The goods have a forward feed beneath and at right angles to the lengths of the needle-bars. When this feed is practically continuous, the 70 needles of each row will sew diagonal lines of stitching across the goods, and as certain needles move in one direction while others move in the opposite direction the result is diagonal lines of stitching crossing each other at angles, 75 whereby a diamond-shaped pattern is produced upon the goods. Other patterns may, however, be produced, which will be explained more fully hereinafter. I prefer to use five needle-bars, because by so doing I am enabled to 80 use fewer needles in each gang than would be the case if a fewer number of needle-bars were employed.

C¹² designates the needle-bars. C' C² C³ C⁴ C⁵ designate rock-shafts for imparting an up-and-down motion to the needle-bars and the needles. (See particularly Figs. 1, 2, 14, and 15.) These rock-shafts are arranged, one behind the other, near the top of the machine and are in the same horizontal plane. They 90 are journaled in the side portions, A A', of the frame. A rocking motion is imparted to them by means of a bar, C⁶, extending fore and aft of the machine outside the portion A of the frame. (See more particularly Figs. 2, 3, and 95 14.) Connection is made as shown between said rock-shaft and the bar C⁶ by means of levers C', rigidly keyed to the outer ends of the shafts. One of these levers is a bell-crank lever having one of its arms pivotally connected to a rod, C⁸, which extends downwardly at an angle and is connected to a crank or ec-

centric, C², on the driving-shaft B. (See particularly Fig. 14.) When the driving-shaft is rotated, the rod C⁸ imparts a to-and-fro motion to the bar C⁶, which operates through the levers C⁷, to impart a rocking motion to all the rock-shafts C¹, &c., in unison. Motion is transmitted from the rock-shafts to the needle-bars by means of crank C¹⁰, (see particularly Figs. 2 and 3,) mounted upon the rock-shafts C¹, &c. The hubs of each of these cranks is provided with a rib or feather, a, (shown more clearly in Fig. 3,) extending through the apertures therein in the direction of the axes of the hubs. These ribs extend into longitudinal grooves in the rock-shafts and extending throughout their lengths. The cranks may therefore be slid along upon the rock-shafts. Motion is transmitted from the cranks by links C¹¹, pivotally connected near one of their ends to said cranks 20 and at the other of their ends to collars c, rigidly secured to sliding rods c', which slide up and down in suitable slideways arranged in carriages D' D² D³ D⁴ D⁵. The needle-bars C² extend between the rods c', near the lower ends 25 of the latter, and are secured thereto by screws or otherwise.

Each of the carriages D', &c., comprises a main portion, d, and upright portions d', arranged near the ends of the main portion d. (See Fig. 3.) The upright portions d' are bifurcated near their upper ends, (see particularly Fig. 3,) and are provided with suitable apertures in the bifurcations, through which one of the rock-shafts, C, &c., extends. The 30 hubs of the cranks C¹⁰ are arranged between the bifurcated ends of the upright portions d' of the carriages. The main portions d of the carriages extend into V-shaped slideways in portions A² of the frame of the machine extending between the side portions, A A'. A 35 traverse from side to side of the machine is imparted to the carriages by means of screw-shafts D⁶ D⁷ D⁸ D⁹ D¹⁰, journaled in suitable bearings in the side portions, A A', of the frame and extending approximately parallel 40 with the rock-shafts C, &c. The screw-shafts D⁶, &c., extend through screw-threaded nuts d', forming parts of the carriages D', &c. (See particularly Figs. 2 and 3.) When the screw-shafts are rotated, the carriages will be moved 45 along. The screw-shafts rotate in unison and at the same rates of speed. I accomplish this, as shown, by imparting motion directly from the main shaft B to one of the screw-shafts, and 50 from the screw-shaft, by means of intermediate gearing and shafting, to the other screw-shafts. The mechanism I employ for this purpose is 55 as follows:

E designates an eccentric or crank on the main shaft B. (See particularly Figs. 5 and 15.) A crank-rod, F, extends from said eccentric or crank to a bell-crank lever, G, loosely mounted upon a portion of the screw-shaft D⁶, which extends beyond the portion A² of the frame. Said portion of the screw-shaft is not screw-threaded. The crank-rod is pivotally connected to one of the arms of said

bell-crank lever. The other arm of said bell-crank lever bears two pawls, e e', arranged upon opposite sides of said arm of the lever. 70 These pawls are adapted to be engaged with ratchet-wheels H H', rigidly mounted upon said screw-shaft, and between which the lever G is arranged. (See particularly Figs. 4 and 5.) The teeth upon one ratchet-wheel are arranged in a reverse direction to those upon the other ratchet-wheel, and the pawls e e' extend in reverse directions. When one of the other pawls is engaging with its ratchet-wheel, the other pawl is moved into such a position that 80 it will not engage its corresponding ratchet-wheel. One of the pawls operates to rotate the screw-shaft in one direction. The other pawl operates to rotate the shaft in the reverse direction. It is essential that the direction of rotation of the shafts should be reversed, because when the carriages D', &c., have made a complete traverse from side to side of the machine it is necessary to return them to their former position, and this may 90 be accomplished, as will be readily seen, by changing the direction of rotation of the screw-shafts. For the purpose of effecting the change in direction of rotation of the screw-shaft D⁶, and through the intermediate mechanism of the other screw-shafts, I employ a device more clearly illustrated in Fig. 4.

I I' designate dogs extending loosely about the shaft D⁶ and rigidly affixed at one of their ends to a rod, I², comprised in the reversing mechanism. The dogs are arranged at opposite sides of the ratchet-wheels H H'. At their upper ends said dogs are provided with toes i, extending toward each other and toward the ratchet-wheels. The rod I² may be moved 105 lengthwise. When so moved it carries the dogs I I' with it. When so moved, the toe on one of the dogs passes under the pawl to which it is adjacent and lifts it out of engagement with its ratchet-wheel, while the toe upon the other dog moves away from under its adjacent pawl and allows the same to engage with its ratchet-wheel. By moving the dogs first in one direction and then in the other the pawls are alternately in and out of engagement with 110 their respective ratchet-wheels, and the screw-shaft is therefore rotated first in one direction and then in the other. The dogs are shifted automatically when the carriages reach the 115 end of their traverse. This I effect as follows:

I² designates a rod extending parallel with the rod I² and above the same. The rod I² extends through suitable apertures in uprights I⁴ upon projections on one of the portions A² of the frame. Rigidly affixed to the rod I² are 120 tappets I⁵ I⁶, provided with wedge-like surfaces i'. Upon the carriage D' are projections I⁷ I⁸, which are detachably secured to said carriage and travel to and fro with the carriage. When the carriage is nearing the end of its 125 traverse in one direction, the arm I⁴ comes in contact with the tappet I⁵. The rod I² is thereby moved lengthwise in one direction. As the tappet moves along its wedge-like surface i'

moves over a wedge-like surface upon a catch, I^9 , which is pivotally connected to one of the uprights I^4 . This catch is provided at its other end with a hook, i^4 , which, as shown more clearly in Fig. 4, extends down beyond the end of a retaining device, I^{10} , which near one end extends loosely about the rod I^3 , and near the other end extends loosely about the rod I^2 . Coiled about the rod I^3 , between the retaining device I^{10} and the upright I^4 , to which it is adjacent, is a spring, I^{11} . When the tappet I has moved sufficiently far over the end of the catch I^9 , the catch is tripped in such manner as to lift the hook i^4 thereon out of engagement with the retaining device I^{10} . The spring I^{11} will then operate to throw the bars I^2 I^3 and the retaining device I^{10} in the direction of the arrow x , Fig. 4, thereby shifting the dogs I I' in one direction and occasioning a reversal in the direction of rotation of the screw, as described. A pin, i^5 , extending through the rod I^3 and a collar, i^6 , rigidly affixed to the rod I^3 , prevents the retaining device I^{10} from moving off from said rods.

The device just described is in duplicate, one being arranged near one end of the rod I^3 , and the other near the opposite end of said rod. When the operation thus described has been completed, the parts referred to are left in the position shown as occupied by the corresponding parts I^6 I^8 I^{12} I^{13} I^{14} , and the parts I^6 I^8 I^{12} I^{13} I^{14} are left in the position shown as occupied by the parts I^5 I^7 I^9 I^{10} I^{11} . The direction of rotation of the screw having been reversed, the carriage then moves in the direction of the arrow y , Fig. 4, the previous operation is repeated at the opposite end of the rod I^3 , the screw again reversed, and so on. By adjusting the arms I^7 I^8 into different positions the length of traverse of the carriage may be varied. I prefer to provide the tops of the retaining devices I^{10} I^{13} with ratchet-teeth with which the hooks i^4 on the catches I^9 I^{12} will engage successively as the retaining devices are drawn beneath them by the movement of the rod I^3 .

It will readily be seen that the rotation of the screw-shaft D^6 is intermittent. This intermittent motion is transmitted from the shaft D^6 through a bevel gear-wheel, f , mounted on said shaft, to the shaft D^8 , (see particularly Fig. 14,) and also to the shaft D^{10} by means of bevel gear-wheels f' , mounted upon a shaft, J , extending at right angles to the screw-shafts outside the portion A of the frame, and meshing with bevel gear-wheels f^2 on the ends of said screw-shafts. It will, therefore be seen that the screw-shafts D^6 D^8 D^{10} rotate in the same direction. The screw-shaft D^8 bears upon its end which extends beyond the portion A of the frame a gear-wheel, f^4 , (see particularly Figs. 1 and 15,) which gear-wheel meshes with another gear-wheel, f^5 , mounted on the screw-shaft D^7 , the screw-shaft D^7 being arranged directly above the screw-shaft D^8 . Upon the other end of the screw-shaft D^7 (see Fig. 14) is arranged a bevel

gear-wheel, f^6 , which wheel meshes with another bevel gear-wheel, f^7 , mounted upon a shaft, J' , journaled in suitable bearing outside the portion A of the frame and arranged above the shaft J . Upon the shaft J' is another bevel gear-wheel, f^8 , which meshes with another bevel gear-wheel, f^9 , upon the outer end of the screw-shaft D^9 . It will therefore be seen that the screw-shafts D^7 and D^9 rotate in reverse directions to the screw-shafts D^6 D^8 D^{10} . I have shown the carriages D^2 D^3 D^5 , which are operated by the screw-shafts D^6 D^8 D^{10} , arranged upon one side of the machine, and the carriages D^2 D^4 , which are operated by the screw-shafts D^7 D^9 , arranged upon the other side of the machine. (See particularly Figs. 2 and 3.) The carriages D^2 D^4 are therefore moved in an opposite direction to the direction of movement of the carriages D^2 D^3 D^5 when the machine is in operation. I have shown more clearly the resulting lines of stitching produced by this means combined with a continuous forward feed of the goods in Fig. 11. Instead of employing screws for imparting the to-and-fro motion to the carriages, racks and pinions or cords or chains passing over pulleys may be employed. The former arrangement I have illustrated in Fig. 12, in which R designates racks rigidly mounted on the carriages above the same, and R' pinions mounted on shafts R^2 R^3 , extending fore and aft the machine, the shaft R^2 receiving motion from a pinion, R^4 , on a shaft, R^6 , corresponding to the shaft D^6 , and receiving motion from the main shaft in manner similar to the shaft D^6 .

In Fig. 13 is illustrated a means for driving the carriages by means of cords or chains, the cords or chains passing around pulleys R^7 on the shafts R^2 R^3 , and also around pulleys R^8 on the portions A A' of the frame, the ends of the cords or chains being attached to the carriages, as shown.

The shuttles in this machine, in addition to their usual reciprocating motion, have a bodily movement from side to side of the machine, which is in unison with the sidewise motion of the needle-bars bearing the needles with which they respectively operate. The shuttle-races L , in which work shuttle-carriers T , which may be of the usual form, are rigidly secured to slider-bars L' , which are arranged in pairs. (See particularly Figs. 16, 17, and 18.) The slider-bars L' are adapted to be slid to and fro in grooved slideways l , formed in castings L^2 , extending between the side frames of the machine. Metal plates l^2 , provided with suitable perforations through which the needles may pass, are rigidly secured to the tops of the blocks L , in which are formed the shuttle-races. Sidewise motion is transmitted to each pair of sliding bars, and consequently the shuttle-races and shuttles, by means of screw-shafts D^{11} D^{12} D^{13} D^{14} D^{15} , deriving motion, respectively, from the screw-shafts D^6 D^7 D^8 D^9 D^{10} , by means of intermediate gear-wheels, D^{16} , mounted on the shafts D^6 , &c., and D^{11} , &c.,

outside the portions A A' of the frame. It will readily be seen that the gear-wheel D¹⁶ will cause the shafts D¹¹, &c., to rotate in reverse direction to the shafts D⁶, &c., with which they respectively act. As, therefore, the shuttles and needles are to move in unison from side to side of the machine, I screw-thread the shafts D¹¹, &c., in a reverse direction to the screw-shafts D⁶, &c. (See Figs. 14 and 15.) The screw-shafts D¹¹, &c., engage with nuts D¹⁷ upon one of each of the pair of slide-bars L', whereby the slider-bars are moved along. (See particularly Fig. 18.)

As shown in the drawings, the needles and shuttles have reached the extreme limit of their sidewise movements, and by referring to Fig. 2 it will be seen that the needles and shuttles are wholly beyond the edge of the goods, the latter being shown in dotted lines in said figure. This is the position the needles and shuttles assume at the end of each traverse, and it is a feature of my invention that the needles and shuttles each pass entirely beyond the goods each time they move from side to side of the machine.

In order to insure the proper working of the machine and obviate the possible entanglement of the needle and shuttle threads when not sewing the goods, I deem it expedient that the usual reciprocating motion of each of the shuttles shall commence exactly at the time when its corresponding needle enters the goods, and shall cease the instant such needle leaves the goods upon the opposite edge. For this purpose I employ shuttle-drivers O, so formed that they act in conjunction with the shuttle-carriers to successively pick up and drop off the shuttle-carriers as they are moved along. These shuttle-drivers are arranged directly beneath the goods and at right angles to the direction of feed thereof, and one of them acts in conjunction with each gang of shuttles. (See particularly Figs. 6, 7, 17, and 18.) They are each rigidly secured to arms O', mounted upon slider-rods O², extending fore and aft the machine and sliding in sideways o upon the under side of the castings L².

A to-and-fro motion is imparted to the slider-rods O² by means of an eccentric, O³, on the main shaft B, from which extends an eccentric-rod, O⁴, pivotally connected at one end to an arm, O⁵, rigidly mounted on a shaft, O⁶, journaled in bearings o² in brackets o³, extending downwardly from one of the castings L². (See Figs. 1 and 3.)

Near opposite ends of the shaft O⁶ are rigidly mounted arms O⁷, which latter have pivotally connected to them near their free ends links O⁸, which latter are in turn pivotally connected to downwardly-extending portions on two of the arms O'. It will therefore be seen that when the main shaft is rotated a to-and-fro motion will be imparted to all the shuttle-drivers simultaneously.

The ends of the shuttle-drivers are beveled both upon the top and upon the sides and are

resilient. (See Figs. 6, 7, 17, and 18.) Each of the shuttle-carriers is provided with two downwardly-extending lugs, p, the space between which is only sufficient to admit of the shuttle-drivers O springing in between them. As the shuttle-carriers are moved from side to side of the machine each is in turn brought in contact with one of the ends of the shuttle-drivers. The end of the shuttle-driver being beveled and resilient, as described, rides under one of the lugs p, and is sprung up between the pair of lugs. I have shown springs p' acting as buffers, against which the shuttle-carriers will be thrown, and which will assist in causing the ends of the drivers O to enter between the lugs p. The shuttle-carrier is then in engagement with the shuttle-driver, and the usual reciprocating motion is imparted to the shuttles. The shuttle-carriers are constantly crowded on at one end of the shuttle-drivers and off at the other end. It will therefore be seen that they have no reciprocating motion except when in engagement with the shuttle-drivers.

A forward intermittent feed is imparted to the goods by means of a ratchet-wheel, S, mounted upon the journal of one of a pair of feed-rollers, S' S², journaled in suitable bearings, s, at the rear of the machine. (See particularly Figs. 3, 8, and 9.) The ratchet-wheel S is actuated by a pawl, S³, mounted upon a swinging arm, S⁴, upon the shaft of the feed-roller upon which the ratchet-wheel is mounted. Motion is imparted to the arm S⁴ by means of an eccentric-rod, S⁵, actuated from an eccentric, S⁶, upon the shaft B.

In Figs. 8 and 9 I have shown means for varying the pattern sewed upon the goods, and in Fig. 10 I have illustrated the pattern made by such mechanism.

Upon the hub of the ratchet-wheel S is loosely mounted another ratchet-wheel, S⁷. This ratchet-wheel is segmental, or, in other words, segments S⁷ only of the wheel are provided with ratchet-teeth. The teeth upon the toothed segmental portions extend beyond the teeth upon the ratchet-wheel S, but the spaces between such toothed segmental portions are inward of the teeth upon the wheel S. The wheel S⁷ receives motion from another ratchet-wheel, S⁸, rigidly mounted upon the hub of the wheel S. A pawl, S⁹, on the wheel S⁷ engages the teeth upon the ratchet-wheel S⁸, whereby the wheel S⁷ is rotated when the wheel S rotates.

It will be seen that motion is imparted to the wheel S only when the pawl S³ is operating opposite the spaces between the toothed segmental portions of the wheel S⁷, or in conjunction with the teeth on the wheel S, for when, by the movement of the wheel S, the wheel S⁷ is carried around far enough so that the pawl S³ will ride up onto the toothed segmental portions of the wheel S⁷ and engage the teeth thereon the wheel S⁷ will thereby be caused to rotate loosely about the hub of the

wheel S, and no motion will be imparted to the latter wheel, and consequently to the feed-rollers. When the pawl has moved the wheel S' around far enough, the pawl will again drop down into one of the spaces of the wheel S' and into engagement with the teeth upon the wheel S, again operating to rotate the latter wheel, and so on. When the wheel S is rotating, the goods are receiving a forward feed, and to the needles are therefore sewing diagonal lines of stitching; but when said wheel is stationary the goods are not being fed, and the needles sew lines of stitching at right angles to the length of the goods, the result being a pattern such as is shown in Fig. 10, in which the arrow indicates the direction of feed of the goods.

On the wheel S' is a circumferential rim or flange, S^o, about which extends a band-brake, 20 S¹⁰, rigidly affixed at one end to a portion of the frame of the machine, and being provided at the other end with a screw-threaded portion, S¹², extending through an eye, s¹, on a bracket, s⁴, rigidly secured to the frame. A 25 nut, s⁵, engaging the screw-threaded portion s¹ and bearing against the bracket s⁴, provides for tightening or loosening the band-brake. This brake steadies the wheel S' and causes it to maintain a position for properly operating 30 with the pawl S³. Upon a bracket, s⁶, extending downwardly from the frame of the machine, I have shown a pin, s⁷, extending into the path of the pawl S³. This pin is so placed that when the pawl is moved backwardly it 35 will strike the pin and be rocked into such position that it will readily engage the teeth upon the two other segmental portions of the wheel S when necessary. I have shown it in such position in Fig. 8. Plates u tend to support the goods when moving through the machine.

I have shown presser-bars for the goods in Fig. 1. Such presser-bars may be of the ordinary or any desired construction. As shown, 45 they consist of bars N, for pressing the goods, rigidly affixed to upright rods n, extending through guides n' on the carriages, and operated by toes on the hubs of the cranks C¹⁰, and adapted to come in contact with projections 50 n² on the upper ends of the rods n. When the said cranks are rocked, springs n⁴, surrounding the rods n, operate to return the presser-bars quickly after they have been raised. It will be observed that the ends of the presser- 55 bars are curved upwardly to facilitate their passage over the goods when the carriages are moving laterally. In a similar manner and for a similar purpose the metal plates l² are curved downwardly at the ends.

60 I have shown a tension device in Fig. 3. I have only illustrated one, but it is to be understood that each needle is to be provided with a similar one. This device consists of a spring, r, rigidly mounted on a portion of 65 the carriage and provided near one end with a loop. Through this loop extends a portion

of another spring, r', also mounted on said portion of the carriage. The spring r' is provided near one end with an eye, r². The needle-thread is wound upon a spool mounted on a spindle upon an arm, r³, rigidly affixed to and extending upwardly from a rod, r⁴, which is in turn rigidly affixed to the carriage. The needle-thread, after passing two or three times around the rod r⁴, extends through the eye r² 75 in the spring r', and thence to the needle. This tension device is of ordinary construction, but any suitable tension device may be used. All the tension devices travel to and fro with their respective carriages. 80

What I claim as my invention, and desire to secure by Letters Patent, is—

1. In a quilting-machine, the combination, with feed-rollers for the goods, of traveling carriages, needle-bars bearing needles mounted 85 on said carriages, guides for the carriages, and mechanism, substantially such as described, for moving the needles wholly beyond the edge of the goods at each traverse of the carriages, substantially as specified. 90

2. In a quilting-machine, the combination, with feed-rollers for the goods, of traveling carriages, needle-bars bearing needles mounted on said carriages, guides for said carriages, mechanism, substantially such as described, 95 for imparting a side-to-side motion to said carriages, slider-bars carrying shuttles acting in conjunction with said needles, said slider-bars being independent of said carriage, shuttle-races, and mechanism, substantially such 100 as described, for imparting a side-to-side motion to said slide-bars, said carriages and shuttle-races moving in unison, substantially as specified.

3. In a quilting-machine, the combination, 105 with feed-rollers for the goods, of traveling carriages, needle-bars bearing needles mounted on said carriages, guides for said carriages, screws for imparting a side-to-side motion to said carriages, shuttle-carriers carrying shuttles acting in conjunction with said needles, shuttle-races, and screws for imparting a side-to-side motion to said shuttle-races, the screws for actuating the carriages and the screws for actuating the shuttle-races being 110 geared together, substantially as specified. 115

4. In a quilting-machine, the combination, 120 with shuttles, of shuttle-carriers, shuttle-races, mechanism, substantially such as described, for imparting a side-to-side motion to the shuttle-races, and a reciprocating shuttle-driver with which the shuttle-carriers are alternately engaged and disengaged when moving in either of two directions, substantially as specified.

5. In a quilting-machine, the combination, 125 with shuttles, of shuttle-carriers, a number of shuttle-races, mechanism, substantially such as described, for imparting a side-to-side motion to each of the shuttle-races, and a shuttle-driver arranged at each of the shuttle-races, with 130 which the shuttle-carriers are alternately engaged and disengaged when moving in either

of two directions, all said shuttle-drivers operating in unison, substantially as specified.

6. In a quilting-machine, the combination, with needle-bars bearing needles and having a 5 movement from side to side of the machine and carrying the needles wholly beyond the edges of the goods, of shuttles operating in conjunction with said needles, and a shuttle-driver for reciprocating the shuttles, and mechanism, 10 substantially as described, for operating the shuttles, whereby the shuttles will be reciprocated only when beneath the goods, substantially as specified.

7. The combination, with a traveling carriage 15 and sewing mechanism, of feed-rollers, a ratchet-wheel on the journal of one of said feed-rollers, another ratchet-wheel arranged at the side of the ratchet-wheel first-named, and having segmental portions provided with teeth, 20 an arm, a pawl on said arm for imparting motion to said ratchet-wheels, and a rod for imparting motion to said arm, the teeth upon the segmental ratchet-wheel extending beyond the teeth upon the ratchet-wheel first named, and 25 the spaces between the toothed segmental portions of said wheel being inward of the teeth

upon the ratchet-wheel first named, substantially as specified.

8. The combination, with feed-rollers, a traveling carriage and sewing mechanism, of the 30 ratchet-wheel S, the segmental ratchet-wheel S', provided with the flange S⁹, the ratchet-wheel S⁸, the pawl S', the brake S¹⁰, the arm S¹, the pawl S³, and the rod S⁵, substantially as specified. 35

9. The combination, with laterally-moving shuttle-races, of shuttle-carriers moving with said shuttle-races and provided with legs, as p, a reciprocating shuttle-driver provided with 40 resilient beveled ends and bumpers for the shuttles, substantially as specified.

10. The combination of sewing mechanism, the rod F, the lever G, pawls c c', ratchet-wheels H H', a screw-shaft, as D⁶, dogs f I', rods I² I³, tappets I⁵ I⁶, catches I⁹ I¹², retaining 45 devices I¹⁰ I¹³, and a traveling carriage, as D⁶, provided with projections I' I', substantially as specified.

KARL ZALLUD.
